UNITED STATES PATENT OFFICE

ALEXANDER F. JENKINS, OF BALTIMORE, MARYLAND

PAINT SPRAYING APPARATUS

Application filed May 23, 1929. Serial No. 365,447.

This invention relates to paint spraying apparatus and more particularly to devices of this general type by means of which paint or similar liquid coating material may be sprayed by means of compressed air, such for instance as is disclosed in my copending application Serial No. 159,849, filed January 8, 1927.

The object of the present invention is to provide an improved mechanism for operating the paint spray valve of such a device which is simple in construction and easy to adjust and operate.

A further object of this invention is the provision of means for adjusting the paint valve operating means to secure a desired sequence of actuation of the paint valve and the compressed air valve, or to effect actuation of the compressed air valve independently of the paint valve, the paint valve adjusting means being actuated from a convenient point at the rear end of the device.

Further objects and features of novelty will be apparent from the following description when read in connection with the accompanying drawing, wherein is illustrated a preferred embodiment of the invention by way of example.

Figure 1 is a side elevation of a spray gun embodying the principles of this invention, with part of the body portion thereof shown in section; and

Figure 2 is a section taken on line 2—2 of Fig. 1 in the direction of the arrows.

In the drawing the body of the paint spray gun, or air brush as it is sometimes called, is indicated generally by the numeral 10, and comprises the forward portion 11 and the rear portion 12 connected by a narrow intermediate portion 13 and an arched hanger and trigger pivot member 14. To the lower part 15 of the rear portion 12 is attached in a suitable manner the handle 16 which is provided with a passageway 17 through which compressed air may pass from the connection 18 to the body portion 10 of the device. To connection 18 is adapted to be attached an air-hose of any suitable type leading from a source of compressed air.

Within the lower part 15 of the body portion is disposed an air valve mechanism for controlling the flow of compressed air from the passageway 17, similar in all respects to the corresponding air valve shown in the copending application Serial No. 159,849, above referred to. This air valve mechanism is shown in Fig. 1 of the drawing in dotted lines. Valve member 19 is pressed against seat 20 by means of the spring 21 which is disposed within the bore 22 between the valve member 19 and the removable closure cap 23 screwed into the end of the bore 22. Valve stem 24 projects forwardly from the bushing 25 in a position to be cammed rearwardly to valve opening position by contact with the raised portion 26 of the trigger 27. Trigger 27 is provided with two arms 28 which straddle the body portion 10 and are pivoted at 29 to the member 14.

Beyond the air valve mechanism, a passageway 30 leads to the longitudinal passageway 31 which passes through the body portion of the spray gun to a point 32 where it divides and two passageways 33 are provided, one on each side of the forward portion 11, to convey the compressed air to the annular air space 34 within the nozzle 35. From the chamber 34 the air issues through the annular orifice 36 and through the supplemental jet orifices 37, the paint being forced through the central orifice 38 by gravity or air pressure acting upon the source of supply or by the siphoning or injector effect of the air passing through the orifice 36.

This nozzle forms part of the subject matter of the above mentioned copending application and is not a part of the present invention except insofar as it cooperates with the novel valve actuating means to be described later. Therefore a detailed description of this element will not be found necessary to an adequate understanding of the operation of this invention.

The constricted end 39 of the valve stem 40, and the tapered portion 41 cooperate with the inner wall 42 of the orifice member 43 to form a needle valve for controlling the

delivery of the paint or coating material from the bore 44 of the forward portion 11 of the body member through the orifice 38. This bore 44 communicates with the vertical passageway 45 which leads to the pipe connection 64. Any usual or suitable means for connecting the supply of paint or other coating liquid to this pipe connection 64 may be provided.

10 Rearwardly of its junction with the passageway 45 the bore 44 is narrowed so as to provide a collar portion 46 which surrounds the valve stem 40 passing therethrough. Between the collar 46 and the plug 47 which 15 is screwed into the rear end of the bore 44 is compressed the packing material 48 forming a customary stuffing box arrangement, for the purpose of preventing leakage of coating material from the bore 44.

15 The rear body portion 12 of the gun is provided with an upper extension 49 which is separated from the forward portion 11 by the space 50 lying above the intermediate portion 13. Through this upper extension 20 passes a bore 51 which is of a larger diameter than the bore 44 of the forward portion and is disposed in longitudinal alignment therewith. The needle valve stem 40 extends across the space 50 and through the bore 51 and is provided at its rear end beyond the bore 51 with an adjusting knob 52. The rear end of the bore 51 is closed by a plug 53 through which the stem 40 passes and which is provided with a hollow 25 cylindrical exterior chamber 54 which encloses the forward end 55 of the knob 52. An abutment 56 is rigidly fixed on the portion of the stem 40 which lies within the bore 51. Surrounding the stem 40 within 30 the bore 51 is a spring 57 which is compressed between the plug 52 and the abutment 56 so as to constantly urge the needle valve toward its seat.

35 Threaded upon the stem 40 near its middle portion is the adjustable cylindrical plunger or abutment 58 which is adapted to be engaged at its forward end by the yoke 59 which is pivoted to the trigger 27 at 60. The bore 51 is provided with a lug or key 50 61 which is fixed thereto and is adapted to engage a slot 62 in the abutment 58 so as to permit sliding movement but prevent rotation thereof.

It will thus be apparent that by turning 55 the knob 52 the plunger or abutment 58 may be advanced within the bore 51 or retracted therein against the action of the spring 57. It will also be seen that the position of the abutment 58 upon the needle valve stem 60 relative to the yoke 59 determines the amount of angular movement of the trigger 27 necessary to actuate the needle valve and consequently the sequence of actuation of the paint valve and the air valve. It will 65 also be noted that the farther the abutment

58 is adjusted forwardly, the greater the travel of the valve stem 40 upon actuation of the trigger 27, and as a result of the paint valve will be opened wider than it would be upon a lesser movement of the stem 40. Furthermore, the abutment 58 may be adjusted rearwardly so far that it will not be engaged by the yoke 59 at all, which will enable the air valve to be actuated alone for the purpose of forcing air through the nozzle orifices for clearing them of obstructions or for any other purpose.

The compression of the spring 58 may be varied to a slight extent by adjustment of the plug 53 within the rear end of bore 51.

When not in use, the spray gun may be suspended from any suitable support by means of the hook 63 formed at the end of member 14.

Although but one form of the invention has been shown and described, it will be evident that various changes and modifications may be made therein without departing from the scope of the invention as set forth in the appended claims.

Having thus described the invention, what is claimed as new and desired to be secured by Letters Patent is:

1. In a spraying device for liquids, in combination, a body having a passageway for a liquid, said body having a longitudinal bore, a valve controlling the flow through said passageway and provided with a seat, a stem for said valve extending through said bore, an abutment threaded upon said stem and non-rotatably disposed partly within the forward end of said bore, said bore and abutment having interengaging portions preventing relative rotation of the body and abutment, spring means within said bore adapted to urge said valve stem toward said valve seat, and means adapted to cooperate with said abutment to withdraw said valve from said seat.

2. In a spraying device for liquids, in combination, a body having a passageway for a liquid, said body having a longitudinal bore, a valve controlling the flow through said passageway and provided with a seat, a stem for said valve extending through said bore, an abutment threaded upon said stem and disposed partly within said bore, means for preventing rotation of said abutment within said bore but permitting longitudinal movement thereof, means for rotating said stem whereby longitudinal adjustment of said abutment along said stem is secured, and means adapted to cooperate with said abutment to actuate said valve.

3. In a spraying device for liquids, in combination, a body having a passageway for a liquid, said body having a longitudinal bore, a valve controlling the flow through said passageway and provided with a seat, a stem for said valve extending through said

- bore, an abutment threaded upon said stem and disposed partly within said bore, means for preventing rotation of said abutment within said bore but permitting longitudinal movement thereof, means for rotating said stem whereby longitudinal adjustment of said abutment along said stem is secured, spring means within said bore adapted to urge said valve stem toward said valve seat, and means adapted to cooperate with said abutment to withdraw said stem from said seat.
4. In a spraying device for liquids, in combination, a body having a passageway for a liquid, said body having a longitudinal bore, a valve within said passageway provided with a seat, a stem for said valve extending through said bore, an abutment threaded upon said stem near its middle portion and disposed partly within said bore, a key within said bore, a slot in said abutment for cooperating with said key whereby only longitudinal movement of said abutment within said bore is permitted, means for rotating said stem whereby longitudinal adjustment of said abutment along said stem is effected, and means adapted to co-operate with said abutment to actuate said valve.
5. In a spraying device for liquids, in combination, a body having a passageway for a liquid, the forward portion of said body having a bore therein, a rear portion of said body spaced from said forward portion and having a bore therein aligned with the first mentioned bore, a valve disposed within said forward body portion and having a seat, a stem for said valve extending through both said bores and across the space between them, an abutment threaded upon said stem and disposed partly within the bore of said rear portion of the body and partly within the space intervening between said forward and rear body portions, means for limiting the movement of said abutment within said bore to a longitudinal direction, means for adjusting said abutment upon said stem, and means cooperating with said abutment to actuate said valve.
6. In a spraying device for liquids, in combination, a body having a passageway for a liquid, a forward portion of said body having a bore therein, a rear portion of said body spaced from said forward portion and having a bore therein aligned with said first mentioned bore, a valve disposed within said forward body portion and having a seat, a valve stem therefor extending through both of said bores and across the space between them, an abutment carried by said stem and disposed within said rear bore, a closure for the rear end of said rear bore, spring means disposed between said abutment and said closure for urging said stem toward said valve seat, a second abutment threaded upon said stem and disposed partly within said rear bore and partly within said intervening space, means for preventing rotation of said second abutment, means for rotating said stem whereby adjustment of said second abutment is effected, and valve actuating means cooperating with said second abutment.
7. In a spraying device for liquids, in combination, a body having a passageway therein for a liquid and provided with a nozzle, a forward portion of said body having a bore therein, a rear portion of said body spaced from said forward portion and having a bore therein aligned with said first mentioned bore, a valve disposed within said nozzle and having a seat, a valve stem extending through both of said bores and across the space between them, an abutment carried by said stem and disposed within said rear bore, a closure for the rear end of said rear bore, spring means disposed within said rear bore between said abutment and said closure for urging said stem toward said valve seat, a second abutment threaded upon said stem and disposed partly within said rear bore and projecting into said intervening space, means for preventing rotation of said second abutment, said stem passing through said closure, means disposed upon the end of said stem rearwardly of said closure for rotating said stem whereby adjustment of said second abutment longitudinally of said stem is effected, and valve actuating means cooperating with said second abutment.
8. In a spraying device for liquids, in combination, a body having passageways therein for liquid and compressed air and provided with a spray nozzle at its forward end and a handle at its rear end, a forward portion of said body having a bore therein, a rear portion of said body spaced from said forward portion and having a bore therein aligned with said first mentioned bore, a valve disposed within said nozzle and having a seat, a valve stem extending through both of said bores and across the space between them, an abutment carried by said stem and disposed within said rear bore, a closure for the rear end of said rear bore, spring means disposed within said rear bore between said abutment and said closure for urging said stem toward said valve seat, said closure being adjustable to regulate the pressure exerted by said spring, a second abutment threaded upon said stem and disposed partly within said rear bore and projecting into said intervening space, means for preventing rotation of said second abutment, said stem passing through said closure, means disposed upon the end of said stem rearwardly of said closure for rotating said stem, whereby adjustment of said second abutment longitudinally of said stem is effected, and valve actuating means cooperating with said second abutment.

effected, a valve for controlling said air passageway, a trigger adapted to actuate said air valve and provided with a detachable connection with said second abutment where-
5 by actuation of said liquid and air valves may be effected either one before the other or the air valve may be actuated independently of the liquid valve.

9. In a liquid spraying device, in combination, a body having passageways therein for liquid and air, a valve controlling the flow through said liquid passageway and having a stem extending longitudinally of said body, an abutment disposed upon said stem
10 near its middle portion, said abutment being longitudinally adjustable upon said stem by rotation of said stem, a valve controlling flow through said air passageway, a stem for operating said air valve longitudinally disposed beneath said liquid valve stem, a trigger pivoted at a point above both of said stems and adapted to contact with and
15 actuate said air valve stem, and means associated with said trigger for operatively engaging said abutment to effect actuation of said liquid valve stem, whereby actuation of said liquid and air valves may be effected either one before the other or the air valve
20 may be actuated independently of the liquid valve.

10. In a liquid spraying device, in combination, a body having passageways therein for liquid and air, a valve controlling the flow through said liquid passageway and
25 having a stem extending longitudinally of said body, an abutment disposed upon said stem near its middle portion, said abutment being longitudinally adjustable upon said stem by rotation of the stem, a valve controlling flow through said air passageway, means for actuating said valve, and means associated with said valve actuating means for operatively engaging said liquid valve and effecting actuation thereof, said last
30 mentioned means being adjustable to permit independent actuation of the air valve, longitudinal adjustment of said abutment upon said stem effecting variation in the relative times of opening of said valves.

50 In testimony whereof I hereunto affix my signature.

ALEXANDER F. JENKINS.
